Attorney

UNITED STATES PATENT OFFICE.

WILLIAM H. BIRGE, OF FRANKLIN, PENNSYLVANIA.

HOT-AIR FURNACE.

SPECIFICATION forming part of Letters Patent No. 698,170, dated April 22, 1902.

Application filed July 5, 1901. Serial No. 67,160. (No model.)

To all whom it may concern:

Be it known that I, WILLIAM H. BIRGE, a citizen of the United States, residing at Franklin, in the county of Venango and State of Pennsylvania, have invented new and useful Improvements in Hot-Air Furnaces, of which the following is a specification.

This invention appertains to air-heating furnaces; and it consists in the construction and arrangement of the parts wherein a large number of hot-air tubes are inclosed within a rectangular casing, said casing having to one side of the same and between the hot-air tubes a perforated plate, the perforations or apertures aggregating in area an opening which is slightly larger than the exit-opening for the products of combustion, so that the heat will be retained and the full effect thereof utilized in heating the hot-air tubes, through which the air passes to a cylindrical top or distributing chamber, as will be hereinafter set forth.

In the accompanying drawings, Figure 1 is a vertical sectional view showing a hot-air furnace embodying my improvements. Fig. 2 is a plan view of one of the top or bottom plates to which the hot-air tubes are connected. Fig. 3 is a front elevation of a perforated plate located within the rectangular casing.

A hot-air furnace made up in accord with my invention may be of the self-feeding type, and to this end a magazine A can be suitably attached or formed as a part of the furnace, and said fuel-magazine A has a contracted throat a, through which the fuel passes to the fire-pot B, below which is the grate and ash-pit. It will be noted that in the construction shown the throat or discharge opening of the magazine is toward the front of the furnace and that the fuel will incline from the rear side of said throat to the rear edge of the fire-pot, so that a comparatively large surface is provided. The feed for the furnace may have the usual doors and dampers and the rear wall of the magazine and fire-pot may form a part of the front wall of the casing, which contains the hot-air tubes.

The casing C, which incloses or contains the tubes D D', is preferably rectangular in cross-section and carries a ledge or support d, upon which the bottom plate E rests, and be-

low said plate is a chamber F, into which cold air is admitted. The tubes D D' are attached to the bottom plate E and to an upper plate 55 E', which upper plate is of greater area than the casing C, so that its edges will bear thereon and support a dome or cylindrical top G, having a number of openings to which hot-air flues can be connected. The top or dome 60 G may be bolted or otherwise connected to the top plate E', and the side walls may converge, so that the top is, as a matter of fact, conical.

H refers to a heat-restraining plate which 65 extends from the bottom horizontal wall or plate E to the top wall or plate E', and the same is provided with a number of perforations the combined area of which exceed the area of the smoke-pipe and opening I for the 70 products of combustion, said opening being but a short distance above the bottom wall or plate E of the furnace.

The function of the heat-restraining plate is to scatter and delay the heat and products 75 of combustion on their way to the chimney, and for this purpose in a hot-air furnace having, say, forty-nine hot-air tubes the plate H will be located between the second and third set of tubes nearest the chimney or stove-pipe.

In operation cold air passes from the chamber F and on its way upward through the tubes is heated, and in its heated condition is carried to the hot-air flues. The products 85 of combustion will keep the flues hot, and in practice those flues which are the hottest will tend to draw through the same the greatest amount of air, and by providing the plate H I utilize all the heat units from the fuel, as 90 in practice the stovepipe or chimney is hardly warm as the smoke and gases pass through the same.

I am aware that hot-air furnaces have been constructed with deflecting-plates to cause 95 the products of combustion to take a circuitous route; but in my invention the heat is scattered, and instead of passing directly to the chimney is divided by the restraining-plate.

I claim—

1. A hot-air furnace comprising a casing having to one side of the same a fire-pot and on the opposite side an exit for the products

of combustion, a plurality of vertically-disposed hot-air tubes carried by top and bottom plates, a dome or top for the reception of the heated air, and a perforated baffle or heat-restraining plate located within the casing and positioned nearer the opening for the exit of the products of combustion than to the fire-pot, substantially as shown.

2. In a hot-air furnace the combination 10 with a casing having on one side a fire-pot and opposite thereto an opening for the exit of the products of combustion said casing containing a plurality of hot-air tubes, a heat-restraining plate located within the casing and provided with numerous apertures the combined area of said apertures exceeding 15 the area of the opening for the products of combustion, substantially as shown.

3. In a hot-air furnace, the combination of 20 a casing which is rectangular in cross-section,

rectangular plates having attached thereto hot-air tubes, a dome or top for the reception of the heated air carried by the upper rectangular plate, an apertured heat-restraining plate positioned between the tubes and 25 extending from the bottom to the top wall of the rectangular casing, an opening for the escape of the products of combustion located near the lower portion of the furnace and a fire-pot which opens into the casing on the 30 opposite side from the escape-opening, substantially as shown.

In testimony whereof I have hereunto set my hand in presence of two subscribing witnesses.

WILLIAM H. BIRGE.
